MANUFACTURING COMPANY, A CORPORATION OF MASSACHUSETTS.

CARBURETER.

1,157,363.

Specification of Letters Patent.

Patented Oct. 19, 1915.

Application filed November 30, 1914. Serial No. 874,703.

To all whom it may concern:

Be it known that I, JOHN O. BLOMQUIST, a subject of the King of Sweden, and a resident of Dorchester and State of Massachusetts, have invented a new and useful Improvement in Carbureters, of which the following is a specification.

My invention is an improvement in carbureters, and has for its object to provide 10 a carbureter adapted for motor vehicles of every character, wherein the flow of fuel from the fuel chamber to the mixing chamber is directly controlled by the throttle valve.

15 In the drawings:—Figure 1 is a vertical section of the improved carbureter, and Fig. 2 is a section on the line 2—2 of Fig. 1, looking in the direction of the arrows adjacent to the line.

20 The present embodiment of the invention comprises a casing 1 of approximately cylindrical form, having a marginal flange 2 at one end for permitting the casing to be connected to the manifold of a motor, and the 25 casing is provided with a lateral inlet 3, which is the air in-take for the carbureter. It will be noted that the entire area of the in-take does not communicate with the mixing chamber, that is, with the interior of 30 the casing 1, but there is a partition wall 4, extending between the intake and the body of the carbureter.

The lower portion of the casing 1 is solid as indicated at 5, and there is an annular 35 trough or groove 6 at the top of the solid portion, this groove or trough being coaxial with the casing 1 and being at the partition 4, which is in fact a continuation of the casing 1. The lower edge of the partition 40 4 extends to near the level of the top of the solid portion 5 of the casing, and passages 7 lead to the trough or depression from a chamber 8 in the lower end of the solid portion 5 of the casing.

45 A series of the passages 7 is provided, the said passages inclining outwardly from the chamber 3 to the trough or groove. The lower end of this chamber 8 is closed by a screw threaded plug 9, the said plug having 50 a transverse kerf for engagement by a

tool to turn the same, and the chamber is internally threaded as shown for receiving the plug.

A passage 10 connects the chamber 8 with another chamber 11 in a nipple 12, which 55 extends downwardly from the solid portion of the casing at the opposite side from the in-take, and the lower end of the chamber 11 is also closed by a plug 13 similar to the plug 9, before mentioned.

60 The upper end of the chamber 11 is formed into a valve seat with which cooperates a needle valve 14, and the seat forms a communication between the chamber 11 and a lateral extension 15 from fuel 65 chamber 16 of the carbureter. The fuel is admitted to the fuel chamber 16, by means of a pipe 17, which leads from a suitable source of supply to a nipple 18 at the lower end and at the center of the fuel chamber, 70 the pipe being threaded into the said nipple.

75 The present embodiment of the invention comprises a casing 1 of approximately cylindrical form, having a marginal flange 2 at one end for permitting the casing to be connected to the manifold of a motor, and the 80 casing is provided with a lateral inlet 3, which is the air in-take for the carbureter. It will be noted that the entire area of the in-take does not communicate with the mixing chamber, that is, with the interior of the casing 1, but there is a partition wall 4, extending between the intake and the body of the carbureter.

85 The lower portion of the casing 1 is solid as indicated at 5, and there is an annular trough or groove 6 at the top of the solid portion, this groove or trough being coaxial with the casing 1 and being at the partition 4, which is in fact a continuation of the casing 1. The lower edge of the partition 40 4 extends to near the level of the top of the solid portion 5 of the casing, and passages 7 lead to the trough or depression from a chamber 8 in the lower end of the solid portion 5 of the casing.

90 A series of the passages 7 is provided, the said passages inclining outwardly from the chamber 3 to the trough or groove. The lower end of this chamber 8 is closed by a screw threaded plug 9, the said plug having 50 a transverse kerf for engagement by a

95 tool to turn the same, and the chamber is internally threaded as shown for receiving the plug.

100 The upper end of the chamber 11 is formed into a valve seat with which cooperates a needle valve 14, before mentioned, is externally threaded at its upper end and is provided with a head 25 for convenience in manipulating the same. The threaded portion engages a threaded opening in a bar 26, to be later described more fully, and by turning the valve in the proper

direction the relative position of the valve and the seat between the extension 15 and the chamber 11 may be varied.

A sleeve 27 is mounted in the casing 1, 5 the said sleeve being the throttle valve, and the lower edge of the sleeve is at the center of the groove or trough 6, before mentioned.

A stop is provided for limiting the downward movement of the sleeve, the stop being in the form of a set screw 28, which is threaded through the bottom of the trough or depression 26 at the in-take 3, and a lock nut 29 is threaded on to the set screw for 15 locking the same in adjusted position.

The inner end of the set screw is in position for engagement by the lower end of the throttle sleeve to limit the downward movement thereof, and the arrangement is 20 such that when the lower end of the sleeve engages the upper end of the set screw the said lower end will be spaced slightly above the bottom of the trough. The passages 7 communicate with the trough just inside of 25 the sleeve as will be evident from an inspection of the drawing.

The bar 26 before mentioned, has its inner end provided with a reduced threaded stem 30, which engages a threaded opening in 30 one side of the sleeve, and the bar extends diametrically of the sleeve. The sleeve is provided with an opening 31 at the opposite side from the opening for the stem 30 through which the bar passes, and the casing 1 has an opening 32 in register with the opening 31.

A shaft 33 is journaled diametrically of the casing 1 above the sleeve, and the said shaft is provided with a radial arm 34 in the 40 casing 1. A link 35 connects the arm with the bar, and it will be obvious that when the shaft 33 is oscillated the sleeve will be moved longitudinally of the casing. The sleeve 27, is as before stated, the throttle valve and the 46 supply of fuel to the trough 6 is controlled by the needle valve 14, which is directly connected with the throttle by means of the bar 26.

The float 22 is so arranged with respect 50 to its stem that normally the fuel will stand in the trough 6 at a higher level than the lower end of the throttle sleeve when the said sleeve rests upon the stop 28. When the piston of the motor is on the suction 55 stroke, air will be drawn in through the intake and will pass downward beneath the lower end of the throttle sleeve and through the fuel in the trough, that is, provided that the throttle is below the level of the fuel in 60 the trough and the air laden with vaporized fuel is drawn up through the casing 1 into the engine.

When the throttle is opened the needle valve 14 is also opened, and the connection 65 between the throttle valve and the needle

valve may be adjusted to suit conditions by turning the valve in the proper direction. In addition it will not be necessary to flood the carbureter on starting, since the mere act of opening the throttle valve to the level of the fuel will increase the supply of fuel to the carbureter. Since there is no resistance or drag to the air because of air valves, springs and dash post, the speed of air past the nozzles and the suction in the intake manifold is determined by the speed of the motor and the opening of the throttle. Usually on quick opening of the throttle at slow motor speed the suction would decrease to a point such that the mixture would be too poor. The high level of the fuel insures a rich mixture at all times. The lower the speed of air taken in the more the fuel overflowing the nozzles tends to enrich the mixture. The relative proportion of air and fuel remains the same under all conditions, because of the high fuel level.

A spring pawl 36 is provided for holding the said nipple valve in adjusted position. This pawl is connected at one end to the bar 90 26 and the other end is adapted to engage the milling of the head 25 for holding the set screw against accidental displacement.

I claim:

1. A carbureter comprising a substantially cylindrical casing having its lower end closed to form a mixing chamber and adapted for connection at the opposite end with the engine, said casing having an annular trough at the closed end coaxial with the casing for receiving the fuel, and having a lateral air inlet at the trough and communicating with the mixing chamber at the outer side of the trough, the carbureter having a fuel chamber, and a float valve for retaining the fuel in the chamber at a predetermined level, said carbureter having an auxiliary fuel chamber at the closed end and communicating with the trough and with the fuel chamber, a needle valve controlling the communication between the auxiliary and main fuel chambers, a throttle sleeve mounted for movement in the casing toward and from the trough and having its lower end at the center of the trough, means for moving the sleeve and a connection between the sleeve and the needle valve for moving the valve in the same direction as the sleeve, said connection comprising a bar arranged transversely of the sleeve, the casing having a slot through which the bar extends, said bar having an internally threaded opening, and the needle valve having a threaded portion for engaging the opening.

2. A carbureter comprising a substantially cylindrical casing having its lower end closed to form a mixing chamber and adapted for connection at the opposite end with the engine, said casing having an annular trough at the closed end coaxial with the

- casing for receiving the fuel, and having a lateral air inlet at the trough and communicating with the mixing chamber at the outer side of the trough, the carbureter having a fuel chamber, and a float valve for retaining the fuel in the chamber at a predetermined level, said carbureter having an auxiliary fuel chamber at the closed end and communicating with the trough and with the fuel chamber, a needle valve controlling the communication between the auxiliary and the main fuel chambers, a throttle sleeve mounted for movement in the casing toward and from the trough and having its lower end at the center of the trough, means for moving the sleeve and a connection between the sleeve and the needle valve for moving the valve in the same direction as the sleeve, said connection being adjustable, and an adjustable stop for limiting the downward movement of the throttle sleeve.
3. A carbureter comprising a substantially cylindrical casing having its lower end closed to form a mixing chamber and adapted for connection at the opposite end with the engine, said casing having an annular trough at the closed end coaxial with the casing for receiving the fuel, and having a lateral air inlet at the trough and communicating with the mixing chamber at the outer side of the trough, the carbureter having a fuel chamber, and a float valve for retaining the fuel in the chamber at a predetermined level, said carbureter having an auxiliary fuel chamber at the closed end and communicating with the trough and with the fuel chamber, a needle valve controlling the communication between the auxiliary and the main fuel chambers, a throttle sleeve mounted for movement in the casing toward and from the trough and having its lower end at the center of the trough, and means for moving the sleeve and a connection between the sleeve and the needle valve for moving the valve in the same direction as the sleeve, said connection being adjustable.
4. A carbureter comprising a substantially cylindrical casing having its lower end closed to form a mixing chamber and adapted for connection at the opposite end with the engine, said casing having an annular trough at the closed end coaxial with the casing for receiving the fuel, and having a lateral air inlet at the trough and communicating with the mixing chamber at the outer side of the trough, the carbureter having a fuel chamber, and a float valve for retaining the fuel in the chamber at a predetermined level, said carbureter having an auxiliary fuel chamber at the closed end and communicating with the trough and with the fuel chamber, a valve for controlling the communication between the auxiliary and the main fuel chambers, a throttle sleeve mounted for movement in the casing toward and from the trough and having its lower end at the center of the trough, and means for moving the sleeve and a connection between the sleeve and the valve for moving the valve in the same direction as the sleeve.
5. A carbureter comprising a substantially cylindrical casing having its lower end closed to form a mixing chamber and adapted for connection at the opposite end with the engine, said casing having an annular trough at the closed end coaxial with the casing for receiving the fuel, and having a lateral air inlet at the trough and communicating with the mixing chamber at the outer side of the trough, the carbureter having a fuel chamber, and a float valve for retaining the fuel in the chamber at a predetermined level, a communication between the fuel chamber and the trough, a valve for controlling the said communication, a throttle sleeve mounted for sliding movement in the casing and having its lower end registering with the trough and adapted to dip therein when the sleeve is in closed position, means for moving the sleeve, and a connection between the sleeve and the valve, said connection being adjustable, and comprising a bar arranged diametrically of the sleeve, the casing having an opening through which one end of the bar extends, and the valve having a stem having a threaded engagement with the bar.
6. A carbureter comprising a substantially cylindrical casing having its lower end closed to form a mixing chamber and adapted for connection at the opposite end with the engine, said casing having an annular trough at the closed end coaxial with the casing for receiving the fuel, and having a lateral air inlet at the trough and communicating with the mixing chamber at the outer side of the trough, the carbureter having a fuel chamber, and a float valve for retaining the fuel in the chamber at a predetermined level, a communication between the fuel chamber and the trough, a valve for controlling the said communication, a throttle sleeve mounted for sliding movement in the casing and having its lower end registering with the trough and adapted to dip therein when the sleeve is in closed position, means for moving the sleeve, and a connection between the sleeve and the valve, said connection being adjustable.
7. A carbureter comprising an approximately cylindrical mixing chamber having one end closed and having an annular fuel trough and having a lateral inlet at the outer edge of the trough, a throttle sleeve movable in the mixing chamber and adapted to dip into the fuel in the trough at one end, a valve for controlling the supply of fuel to the trough, and a connection between the sleeve and the valve for moving the valve in the same direction as the sleeve.
8. A carbureter, comprising a mixing

chamber having one end closed, and having a fuel or aspirating trough at the said end, an inlet at the trough, a throttle valve movable in the mixing chamber and adapted to dip into the fuel trough, a valve for controlling the supply of fuel to the trough, and a connection between the throttle valve and the fuel supply valve for causing the said valves to move together.
